UNITED STATES PATENT OFFICE.

GILBERT W. GOODRIDGE, OF BRIDGEPORT, CONNECTICUT, ASSIGNOR TO THE BEYANT ELECTRIC COMPANY, OF BRIDGEPORT, CONNECTICUT, A CORPORATION OF CONNECTICUT.

ELECTRIC-RANGE SWITCH.

1,323,760.

Specification of Letters Patent. Patented Sept. 13, 1921.

Original application filed October 5, 1917, Serial No. 194,932. Patent No. 1,323,047, dated November 25, 1918. Divided and this application filed September 29, 1918. Serial No. 327,066.

To all whom it may concern:

Be it known that I, GILBERT W. GOODRIDGE, a citizen of the United States of America, and a resident of Bridgeport, in the county of Fairfield and State of Connecticut, having a post-office address care of The Bryant Electric Company, Bridgeport, Connecticut, have invented certain new and useful Improvements in Electric-Range 10 Switches, of which the following is a specification.

My invention relates to electric switches and particularly to switches for controlling the connections for the heating elements of an electric range, the object of my invention being to provide an improved general installation of this type and also an improved switch construction.

The present application is a division of 20 my co-pending application Serial No. 194,932, filed October 5, 1917.

It has been common practice to control the heater units of electric ranges by switches of common type, not particularly designed for 25 this service, and to mount them in exposed position upon the front plate of the range in the ordinary manner of surface switches. This not only exposes them to the danger of injury during shipment and use, but is a 30 more or less make-shift practice, lacking in good workmanship and design with respect to the particular needs of the installation. Moreover, the ordinary surface switch comprises merely a one-piece base, so that in case 35 of injury thereto or derangement of the mechanism carried thereby, it is necessary to discard the entire switch unit and replace it by a fresh one. This entails renewed connections to the mains and heater lines for the 40 substitute switch. Inasmuch as the repair of the installation is frequently undertaken by persons not skilled in the art, the connections are likely to be wrongly made, with the accompanying danger to the operator of 45 the range as well as to the heater unit and the general installation. This is particularly apt to occur if a different make of switch is substituted for the defective one, and it often happens that another switch 50 of the same make as the one replaced is not readily available.

I am aware that in some cases a protective shield has been mounted over flush switches so installed, and that the shield has been

perforated to permit the switch operating 55 thumb pieces and stems to project therethrough; but the latter are still exposed to injury during shipment. Moreover, no improvement is afforded with respect to the other matters above mentioned. 60

The present invention provides an installation particularly designed with reference to the needs of an electric range, and having the advantages of: first, a protected base to which the line and heater connections may 65 be made, and an independent detachable switch block carrying the switch terminals and mechanism, the switch block being readily assembled on the base by securing screws which establish the electrical connections. 70 It is thus possible to make the important connections to the line and heater at the factory, leaving the switch block, which is apt to be injured in transit, to be assembled when the range is installed; and, second, a 75 special casing for the battery of switches and by which the switches are carried, thus eliminating the necessity of drilling and tapping holes in the range front for the holding screws of each switch. To these 80 principal advantages various detail features of improvement in arrangement and construction will appear from the following specification and the accompanying drawings, in which— 85

Figure 1 is a front elevation of portion of a range showing a switch installation in which my invention is embodied in one form;

Fig. 2 is a section on the line 2—2 of Fig. 1;

Fig. 3 is an enlarged face view of the connection block;

Fig. 4 is a section such as Fig. 2, but showing a modified construction; and 95

Fig. 5 is a section on the line 5—5 of Fig. 4.

The present switch installation is illustrated in association with portion of an electric range. One of the several electric 100 heating units 10 commonly employed in a range is shown mounted as usual in the top plate 11 of the range. Upon the front vertical wall 12 of the range is mounted a group of switches, one for each heating unit. 105

The leads 13, 14 and 15 from the high, low and medium resistance connections of each heater unit are carried through a hole

16 in the front plate 12 beneath each switch, passed through separate holes 17 in the insulating connection block 18 and secured to their respective terminal plates 19 mounted 5 on the outer face of the block. The power mains 20 and 21 which run along the inner face of the front wall 12 of the range are tapped at each switch by branch leads 22 and 23, which also pass out through the 10 hole 16 and through holes 24 in the block 18 to their terminal plates 25 on the latter. Each connection block 18 is secured to the wall 12 by screw bolts 26 passing through the connection block and taking into tapped 15 holes in the wall. It will be noted that the block 18 is of less thickness than the marginal overhang 27 of the range top, and is thus protected by the latter from mechanical injury during shipment of the range. 20 At the same time all the connections to the mains and to the heater units may be made at the factory, leaving to the electrician who installs the range only the assembly of the several switches 29 upon the several 25 blocks 18.

The detail construction of the switch does not enter into the subject matter of the present divisional application, and it suffices to point out that each switch base 29 carries 30 switch terminals as shown in my co-pending application, adapted to be electrically connected to the several terminal plates 19 and 25 on the connection block by screw bolts, of which one is shown in Fig. 2 at 35 30. The proper positioning of the switch base on the connection block 18 is assured by a lug 31 on the outer face of the block which takes into a corresponding notch in the juxtaposed face of the switch base. 40 This lug is also engaged by the switch casting 32 which is thereby not only held against rotation, but located in such position that the indicating dial 33 mounted thereon is properly associated with the switch mechanism. The installing electrician, therefore, 45 has only to mount the several switch bases on the several connection blocks 18, an operation which is quickly and readily done by screwing the bolts 30 of the several terminals 50 of each switch into the tapped holes in the several terminal plates 19 and 25 on the blocks 18. Inasmuch as the proper positioning of each switch on its block 18 is located by the boss 31, and all the connections 55 for the mains and heater branches to the block are already made, it is obvious that the installation of the switches may be made by an electrician of ordinary skill and not especially familiar with range conditions, 60 or even by a layman. In a construction of this type it is possible to pack the switches in a special independent receptacle wherein they are protected against injury during shipment.

In the modified construction shown in

Figs. 4 and 5, the battery of switches for the range is mounted within a special casing 34 common to all the switches and secured in any suitable manner on the front wall 12 of the range. The casing has its face 35 inclined outwardly from top to bottom in order to present the switch operating thumb pieces 36 and the indicating dials 33 in a position more convenient to the attendant. The connection block 37 which is here shown 70 of rectangular shape carries the terminal plates for the main and heater branch leads as in the construction first described, but instead of being mounted on the front wall of the range is hung by straps 38 from the face 75 35 of the casing 34. The switch bases 29 may therefore be shipped separately and assembled upon the connection blocks 37 after the range is installed, just as in the construction first described. 80

Various other modifications will readily occur to those skilled in the art which do not depart from what I claim as my invention.

I claim—

1. The combination with an electric range having a front wall and overhanging top, of an electric switch having a base supported in protected position on said front wall below the overhang, main and branch terminals on the outer face of said base, and an independent switch body adapted to be secured to said base and having switch terminals adapted to be electrically connected to the corresponding main and branch terminals on the base, substantially as described. 95

2. The combination with an electric range having a front wall and overhanging top, of a series of electric switches having bases supported in protected position on said front wall below the overhang, a casing common to said switches and serving to support the same in position, main and branch terminals on the outer faces of the switch bases and independent switch bodies adapted 105 to be secured to said bases and having switch terminals adapted to be electrically connected to the coöperating main and switch terminals on the several bases. 110

3. The combination with an electric range 115 having a front wall, of a switch casing mounted on said wall and having an inclined side face, a battery of switches supported by said inclined wall of the casing, and means for leading to said switches main 120 and branch wires, for the purpose described.

4. The combination with an electric range 125 of an insulating block mounted thereon in accessible position, electric terminals on said block, mains leading to the range and electrically connected to certain of said terminals on the block, a heater unit for the range, a group of heater resistance connections extending therefrom to certain other terminals on said block, together with an independent 130

switch member comprising an insulating base adapted to be mounted on said block, and switch terminals electrically connected to the terminals on said block on the installation of the switch.

5. The combination with an electric range, of an insulating block mounted thereon in accessible position, electric terminals on said block, mains leading to the range and electrically connected to certain of said terminals on the block, a heater unit for the range, a group of heater resistance connections extending therefrom to certain other terminals

on said block, together with an independent switch member comprising an insulating base adapted to be mounted on said block, and switch terminals electrically connected to the terminals on said block on the installation of the switch, and means for locating the switch terminals and the terminals on the block in predetermined relationship on the assembly of the parts.

0 In testimony whereof I have signed my name to this specification.

GILBERT W. GOODRIDGE.
